THREADING TOOL

William M. Emery, Cleveland Heights, Ohio, assignor to The Oster Manufacturing Company, Cleveland, Ohio, a corporation of Ohio

Application July 8, 1938, Serial No. 218,109

8 Claims. (Cl. 10—89)

This invention relates to threading tools for pipes, bolts and rods, and is particularly directed towards a hand operated die stock tool with a geared drive to give an advantageous power ratio; together with more efficient feed arrangements, quick release, quick reset, and adjustment for over or under size threads which is not thrown out by release or resetting of the tool; and capability of using the same die stock to cut different types of threads, for example either American-Briggs or Whitworth.

Another purpose of my die stock is to retain the benefit of a lead screw without actually using such a screw, and without its disadvantages, and still another purpose is to assist the initial engagement of the tool with the work.

In general, my invention gives to the user a more smoothly cutting tool, less fatiguing to the operator, easier started, quicker in action, and more adaptable than has previously been known.

Although shown and described as a hand-operated die stock, and primarily intended to be so used, it will be obvious that the invention is not limited to manual operation, but is applicable either in all particulars or in various details to power stocks.

One of the advantages in connection with my gear drive is that the direction of rotation of the handles is the same as the direction of the rotation of the dies upon the work, just as in an ordinary stock, so that the operator is not confused by any opposite movement of parts.

To the accomplishment of the foregoing and related ends, said invention, then, consists of the means hereinafter fully described and particularly pointed out in the claims.

The annexed drawings and the following description set forth in detail certain mechanism embodying my invention, such disclosed means constituting, however, only some of various mechanical forms in which the principle of my invention may be used.

In said annexed drawings:

Fig. 1 is an axial central section through a preferred form of my threading tool on the plane I—I of Fig. 2, with certain features in elevation;

Fig. 2 is a transverse section on the plane II—II of Fig. 1, with certain features in elevation;

Fig. 3 is a plane development of a lead cam slot;

Fig. 4 is a plane development of a modified lead cam slot;

Fig. 5 is an axial section through a modified

form of my invention, on the plane V—V of Fig. 6, with certain features in elevation;

Fig. 6 is a face view of Fig. 5, looking in the direction of the arrow VI;

Fig. 7 is a detail of a modified drive means, 5 applicable to the tool either of Fig. 1 or of Fig. 5, and on the same plane as the upper forward portion of either Fig. 1 or Fig. 5; and

Fig. 8 is a detail illustrating an arrangement both to prevent dies from falling out of the die head, and to tend to expand them. 10

Referring now to Figs. 1 and 2, my improved die stock comprises a barrel 1 with a sleeve 2 on the rear and a die head 3 on the front. Relative movement is allowed both axially and circumferentially between the sleeve and the barrel, and circumferentially between the die head and the barrel. The sleeve carries the usual gripping and centering fingers 4 adapted to engage the work through cam slots 5 in the barrel and operated by a conventional scroll plate 6 and handle 7. The movement of the cam slots 5 along the inwardly projecting ends of the fingers 4 gives a starting and leading motion directly to the barrel, and with it to the die head, as described 15 hereafter. An adjusting ring 9 is threaded to the forward end of the sleeve 2, and can be set in adjustment by the lock screw 10 or other suitable means. This ring 9 adjusts the dies 8 in a manner explained later. The die head 3 carries 20 the usual dies or chasers 8.

The die head assembly is composed of various elements and attachments of a planetary gear system. The foundation ring or reactive gear is a toothed-ring 15 shown in Fig. 1 as keyed by 35 screws 16 to the barrel 1, although of course it could be integral. The planetary pinions 17, of which there are two in the present form, are carried on shafts 18 in a cage whereof the front member is the die head 3 and the rear member 40 a ring 19 rotatable on the barrel 1 and against the rear face of 15, front and rear members being fastened together by bolts 20. A driving ring 25 with an inner toothed flange 26 rotates over 45 the edges of the die head 3 and ring 19, with the flange 26 guided therebetween. Since the dies 8 are held in sockets 30 on the die head 3, the effect is that the dies are carried by a planetary cage and driver at a 3:5 ratio in this particular instance. The ring 25 has the usual handle sockets 27.

The dies 8 are bottomed upon faces 32 outwardly and rearwardly inclined along axially directed receding studs 34, the front ends of which project through suitable openings at the 50 55

bases of the die sockets 30, and the rear ends of which are notched to the adjusting ring 9. The inclination of the faces 32 obviously determines the taper of the thread cut, and thus faces 32 with zero inclination (parallel to the axis) will cut straight threads.

The faces 32 terminate rearwardly in sharply sloping shoulders 36 followed by notches 38. The length of the faces 32 determines the longest cut 10 for which the tool is designed. There is a receding stud for each die, and at least some of these receding studs may project some distance in advance of the die head 3 to carry nuts 35 threaded on such projections, and short springs 35' between such nuts and the face of the die head. In the embodiment illustrated in Figs. 1 and 2, there are four receding studs, of which two opposite ones have springs while the other two, 15 34', do not project so far forward and do not carry springs. The springs 35' assist starting the dies on the work, as explained later.

A suitable arrangement for preventing the dies 8 from falling inward is shown in Fig. 8. A spring-pressed detent 40, attached to the face plate 3 (or 103, Fig. 6) engages a nick 41 in the edge of the die strongly enough to hold the die against gravity, and the nick 41 is shaped or positioned to tend to press the dies radially outward against receding faces 32.

30 It is apparent from Fig. 1 that the studs 34 will be set forward or back with respect to the dies and die head by the position of the adjusting ring 9, to which they are engaged by a groove for axial movement. Such setting, which is made 35 before work begins, obviously varies the initial radial position of the dies 8, thus causing a deeper thread to be started and carried through if the studs are back, or shallower if they are forward, but without altering either the starting 40 position along the axis of the work, or the taper of the thread. Since the faces 32 are somewhat longer than the distance to be threaded, and the axial adjustment which the ring 9 can produce is relatively slight, such adjustment will 45 not cause the dies to drop into the notches 38 too soon.

The cam slots 5 feed the die head upon the work without relying upon the chaser teeth to do their own feeding. These slots 5 fit over the inner ends 50 of the locking fingers 4. The fingers 4 do not move relatively to the pipe, and for this reason the fingers 4 and sleeve 2 act as a fixed base for all the movements of the die stock and its parts, but the barrel 1 is subject to the reactive force on 55 the gear 15, which tends to turn it in the opposite sense to the die head. Such tendency is directed by the cam slots 5 (or 105, Fig. 5) to assist in the starting of the dies upon the work, but the action of the cam slots is not a positive determination 60 of movement, but only a tendency supplementing but subordinate to the force of advance of the die head as the dies cut their way onto the work. With my invention it is accordingly possible to cut threads of different characteristics with the 65 same die stock, of course using the proper dies, either Whitworth, U. S., Standard, or others.

The exact cam formation is obviously a matter 70 to be related to the character of the thread being cut, the character of the dies selected to cut the thread, and other factors, and the cams are so designed to give more or less starting force and leading effect. One form of cam is shown developed in Fig. 3, wherein it will be seen that the rearmost or starting portion of the cam is a curve 75 whose initial slope B is in this particular illustra-

tion 60° to the axial line of the tool, flattening at C to a slope of 15°, and further flattening out to zero at D, at the front end. It will be understood that these values are illustrative and not limiting. The purpose is to bring the die teeth 5 quickly into engagement with the pipe, and feed at the proper rate for thread cutting as determined by the die teeth, but with the principal feeding stress on the cam instead of on the teeth.

The cam of Fig. 3 is recommended for cutting 10 a taper thread. With such a thread the amount of metal removed by the die throat is greatest at the beginning of the cut, and progressively diminishes; therefore the amount of "pull on" is greatest at the beginning and diminishes as the 15 threading progresses, and the curve of the cam is thus accordingly designed with the slope greatest at the beginning.

Where a straight thread is to be cut, the 20 amount of metal to be removed by the dies is constant throughout the length and thus a straight cam such as 5', Fig. 4, is satisfactory. In Fig. 4, another flat development, the portion of the barrel is indicated as 1' and except for the shape of the cam it is the same as the barrel 1 of Fig. 1, 25 or the barrel 101 of Fig. 5. A finger 4 fills the end of the cam slot, and the specific cam illustrated makes an angle of 15° with the axial line A—A of the barrel, as illustrated by the center line E.

A further "pull on" effect may be obtained by 30 means of the springs 35', Fig. 1, already mentioned. These springs tend to move the die head 3 towards the fingers 4, sliding the barrel 1 through the sleeve 2. Thus when the fingers 4 are clamped on the pipe or rod, and the springs 35' 35 compressed, with the throats of the dies 8 on the end of the work, the springs have a "pull on" effect, which lasts until advance of the die head releases the compression.

A modified form of my improved threading tool 40 is shown in Figs. 5 and 6. Elements on these figures which correspond to Fig. 1 are indicated, so far as appropriate, by reference characters 100 higher than on Fig. 1. In Fig. 4 a work piece W, in the present instance a pipe, upon 45 which threading is about to commence, is shown in the tool. The rear end of the tool is clamped as in Fig. 1 by fingers 104 passing through slots 105 in the barrel 101. The planetary gearing arrangements are likewise the same, consisting of 50 an outer ring 125 from which power applied by handles in sockets 127 is transmitted by an internally toothed gear 126 to planetary pinions 117 which also mesh with the inner gear 115, shown integral with the barrel 101 in this form. 55

The dies 108 in the die head 103 are bottomed on the receding faces 132 of studs 134, and the studs are notched as at 138 to allow the chasers to move outward at the termination of their cut. The adjustment of the posts 134 for full, medium 60 or shallow cut is by their connection with a spider 50 movable toward or from a stop bar 52 by a wing headed screw 53. The stop bar contacts the front end of the work W, and a pin 55 prevents relative rotation between the bar 52 and the 65 spider 50, so that the screw 53 will not be tightened or loosened by rotation of the die head 103. The dies 108 may be held against falling inward by the same means as shown in Fig. 8. It is evident from the drawings that varying the space 70 between the bar 52 and spider 50 alters the initial radial position of the dies 108 without changing their axial relation to the tool, so that full, medium or shallow threads may be cut, just as by adjusting the ring 9 of Fig. 1.

In either form of the invention, compound planetary gears 17A, 17B, Fig. 7, may be used instead of the simple planetary gears, the driving and reactive gears 26A and 15' being appropriately altered to fit the situation, all as shown in Fig. 7, where the reference characters correspond to those of Fig. 1, with suffix A, and the spur gear has a large circumference 17A and a small circumference 17B.

10 The operation of the form of invention shown in Fig. 1 will now be described, and that of the form shown in Fig. 5 will be described in those particulars wherein it differs.

The pipe, rod or bolt is inserted in the barrel 15 and clamped in the usual manner with the throat or entering edges of the dies in engagement with the end of the pipe. In the subsequent operations, the studs 4 and sleeve 2 act as a base toward which the die head of the tool is drawn, chiefly by 20 action of the cam slots 5, and spring 35' (if used), since one object of the invention is to relieve the die teeth from feeding work. The handles 27 are now rotated in the cutting direction, and this motion is transmitted by the 25 planetary reduction gear to the die head 3, thus moving the dies in the same direction as the handles, but at a reduction preferably on the order of 5:3, say 1.7:1. With the compound pinions of Fig. 7 this may be of a considerably 30 higher order, in excess of 2:1.

As soon as frictional contact is made between the dies and the work the reaction turns the barrel 1 oppositely to the die head, causing the cam slot to travel on the studs 4 and so first 35 start the dies and then feed them. If the cam slot is that of Fig. 3, for taper threading (the usual situation), the barrel moves at first with a substantial circumferential component, and a slight axial component, as indicated by slope B, 40 but the proportions of circumferential and axial components gradually reverse, for reasons heretofore explained.

The dies are of course of proper size for whatever work is to be cut, according to standard 45 practice, but a variation of a few thousandths of an inch in thread depth is desirable, since for some purposes it is useful to have the thread deeper than for others. This is accomplished as already explained by setting the ring 9 or the 50 screw 53. If a long thread is cut the dies automatically open when they travel back to the notches 38, and in so opening the slopes 36 cause the roots of the threads to work out with a smooth finish instead of an abrupt bur. The 55 notches 38 also serve as safety devices to disengage the dies from the work if a power-driven die stock is left running. After the dies are disengaged the die head turns idly and thus no damage will result no matter how long the drive 60 continues.

If only a short thread has been cut, the tool is removed from the work without unwinding, as follows. The operator releases the fingers 4 by the handle 1 and pulls the rear end of the 65 tool (sleeve 2 and associated parts 6, 7 and so on) toward the die head 3. This slides sleeve 2 over the barrel 1 so that the notches 38 come under the dies 8, and the dies 8 are thus allowed to move radially outward, biased thereto by 70 detents 40 acting on the appropriate slopes of notches 41, and further assisted, if necessary, by the operator rocking the tool on the pipe. With the dies free, the tool is easily removed, and it is reset by pulling the die head and the clamping 75 end in opposite directions.

In the form shown in Fig. 5, the threading tool is fastened on the work W as in Fig. 1, the gear drive is the same (or that of Fig. 7), and the feed by the cam slots 105 will be shaped appropriately to the work, as already discussed in describing Figs. 3 and 4. The adjustment for full or shallow threads is by the spider 50 and stop bar 52, all heretofore described. When the tool is clamped on the work by the fingers 104 the adjusting elements can be pushed back by 10 hand until the bar 52 stops against the front end of the work, and this places the dies 103 in proper radial position. To cut threads with the tool of Fig. 5, the handles are turned just as in Fig. 1, and the effect is as described for 15 that figure. At the end of the cut the dies 103 fall into the notches 138 and the tool can then be pulled forward off the work by releasing the fingers 104.

When a short thread is to be cut either manually or by power, but especially when operating by power, the operator can end the cut by pulling the spider 50 forward until the dies 103 slide down the shoulders into the notches 138, clearing the work. The shoulders act in the same 25 manner as the shoulders 36 in guiding the die teeth gradually out of the work while the threading action is still going on, and so finishing the threads without a bur.

From the foregoing it will be seen that I have 30 invented a threading tool in which an advantageous gear ratio is obtained in a hand tool, reducing the pull which the operator has to exert, without increasing the size or weight of the tool. The direction in which the user turns the handles is the same as the direction in which the cutting is accomplished, and in other respects the 35 operation of the improved tool is familiar. The use of a lead screw is avoided without loss of its advantages. Unwinding the tool to take it off 40 the pipe and to reset the lead screw is eliminated. Once set for any depth of cut, the setting can always be brought back without adjustment by pulling the front and rear parts away from one another.

The elimination of a lead screw offers numerous advantages. It saves the trouble and time of unwinding after a cut; it prevents jamming and breakage; it permits threads of different lead to be cut by the same threading tool 50 with different dies.

As to the saving of time, the provision of notches on the receding studs is an advantage in combination with the cam slot, because by the use of the two features no unwinding, either 55 of the chasers off the pipe or of the parts of the tool between themselves, is needed. The receding stud notch does not save time where a lead screw is used because unwinding of the lead screw governs the time required, and takes as long 60 whether or not the chasers have to be backed off the cut threads.

Although cutting a thread with the present tool (geared 3:5) takes 66% more turns of the handle than a gearless die stock requires to cut 65 a thread of the same length, nevertheless for the total cycle of one cut 16 2/3% fewer turns are needed than with a lead screw tool, because there is no backing off or unwinding.

Other modes of applying the principle of my 70 invention may be employed instead of the one explained, change being made as regards the mechanism herein disclosed, provided the means stated by any of the following claims or the equivalent of such stated means be employed. 75

- I therefore particularly point out and distinctly claim as my invention:
1. In a threading tool, a barrel, a work-clamping assembly on the rear of said barrel axially movable with relation thereto, a die head on the forward end of said barrel and rotatable with respect thereto, a driving ring rotatable with respect to the forward end of said barrel and to the die head, and gear connections between said driving ring, said die head and said barrel.
  2. In a threading tool, a barrel, a work-clamping assembly on the rear of said barrel axially and circumferentially movable with relation thereto, a die head on the forward end of said barrel and rotatable with respect thereto, a driving ring rotatable with respect to the forward end of said barrel and to the die head, and gear connections between said driving ring, said die head and said barrel.
  3. In a threading tool, a work gripping assembly comprising a ring and work-clamping studs therein, a barrel movable within said ring, cams on said barrel engaging said studs and adapted to guide movement of said barrel with respect to said studs, a die head rotatable with respect to said barrel, and gear connections between said die head and said barrel.
  4. In a threading tool, in combination, means for clamping a work piece, a die head rotatable with respect to said clamping means, die carrying means in said die head, studs extending longitudinally through said die head at points radially disposed from the center of said head, faces on the inner sides of said studs inclined outwardly from front to rear, bottom faces on said dies coacting with said inclined faces and adapted to rest thereon, a ring threaded to said clamping means and engaging the rearward extensions of said studs but rotatable relatively to said extensions.
  5. A thread cutting tool comprising in combination a work piece receiving member, a die carrying member rotatably mounted on said work piece receiving member, a driving member coaxially and rotatably mounted on said die carrying member, and a planetary reduction gear train drivably connecting said driving member to said
- die carrying member and to said work piece receiving member, clamping means for attachment to the work piece and cam means connecting said work piece receiving member to said clamping means and so constructed and arranged as to transmit rotative movement imparted to said work piece receiving member into axial movement of said work piece receiving member.
6. In a threading tool in combination, a die head and a driving ring both rotatable on a common axis, planetary reduction gear connections between said driving ring and said head adapted to rotate said head slower than said ring but in the same direction, a work piece receiving barrel differentially connected to said gear train, and cam means connecting said barrel to the work piece for urging said barrel in the same axial direction as that of said die head during thread cutting operation.
7. In a threading tool in combination, a die head and a driving ring both rotatable on a common axis, planetary reduction gear connections between said driving ring and said head adapted to rotate said head slower than said ring but in the same direction, a work piece receiving barrel differentially connected to said gear train, a work piece clamp with respect to which said barrel is slidable, and a cam of compound curvature on said barrel engageable with a fixed bearing element carried by said work piece clamp.
8. In a threading tool, a work piece receiving member, a die carrying member with radially movable dies rotatably mounted on said work piece receiving member, a driving member coaxially and rotatably mounted on said die carrying member and a reduction gear train drivably connecting said driving member to said die carrying member and to said work piece receiving member, clamping means for attaching said work piece receiving member to the work piece, axially extending studs mounted in said die carrying member and having inclined faces adapted to bear against and radially move said dies, and means for longitudinally adjustably connecting said studs to said clamping means.

WILLIAM M. EMERY.
